INVENTOR,

FRANK F. HOSMER

BY MARTIN O. GUINN, ATTY.

UNITED STATES PATENT OFFICE

2,028,778

CAN OPENER

Frank F. Hosmer, Glendale, Calif.

Application December 3, 1934, Serial No. 755,682

3 Claims. (Cl. 30—3)

My invention relates to a can opener and has for its principal object, the provision of a relatively simple, practical and inexpensive device that may be utilized for the convenient and rapid opening of cans.

A further object of my invention is, to provide a can opener having means carried by a pair of pivotally connected jaws and handles for clamping the bead on the edge of a can, one of 10 said jaws carrying a puncturing and cutting blade and the other jaw carrying means for rotating the can against the cutting blade so as to cut a smooth edged disc from the end of the can immediately adjacent the bead thereon and 15 thereby cut a circular opening of the largest possible size in the end wall of the can.

A further object of my invention is, to provide a can opener of the character referred to, having a crank handle and enmeshed pinions for 20 conveniently imparting rotary motion to the toothed wheel that rotates the can during the cutting operation.

With the foregoing and other objects in view my invention consists in certain novel features 25 of construction and arrangements of parts that will be hereinafter more fully described and claimed and illustrated in the accompanying drawing in which:

Fig. 1 is a side elevational view of a can opener 30 of my improved construction.

Fig. 2 is a plan view of the device.

Fig. 3 is an elevational view of the device taken looking in the direction indicated by the arrow 3—3 in Fig. 2.

Fig. 4 is an enlarged horizontal section taken 35 on the line 4—4 of Fig. 1.

Fig. 5 is an enlarged vertical cross section taken on the line 5—5 of Fig. 1.

Fig. 6 is a perspective view of the combined 40 puncturing and cutting blade utilized in my improved can opener.

Referring by numerals to the accompanying drawing which illustrates a preferred embodiment of my invention, 10 designates a short 45 section of strap metal, the rear end of which is bent into a horizontal plane to form a handle 11 and the forward end of the strap is bent outwardly to form a jaw 12 that occupies a plane offset from and parallel with that portion of the 50 strap that connects said jaw and the handle 11.

Member 10 is pivotally connected preferably by 55 means of a rivet 13, to the vertically disposed leg 14 of a combined jaw and handle and the upper portion of said leg is curved rearwardly so as to occupy a position above the member 10 and the rear portion of this member is bent so as to occupy a substantially horizontal plane to form a handle 15 that is positioned above and spaced apart from handle 11.

60 The horizontally disposed leg 16 of the

L-shaped member which functions as a jaw, occupies a position just below and to one side of the jaw member 12 and the strap from which the L-shaped member is formed is extended outwardly at right angles from the forward end of 5 of the jaw 16 and thence rearwardly parallel with and spaced apart from said jaw 16, as designated by 17.

A shaft 18 has its ends journaled in the forward 10 portions of members 16 and 17 and mounted on said shaft and retained thereon by a set screw 19 is a pinion 20.

Shaft 18 extends a short distance beyond member 17 and suitably secured to the projecting end 15 is one end of a crank handle 21.

Journaled in the rear portions of members 16 and 17, is a shaft 22, the forward end of which projects a short distance beyond jaw member 16 and mounted on this shaft and secured by a set screw 23 is a gear wheel 24 that meshes with 20 pinion 20.

The end of shaft 22 that projects through member 16 is threaded and screw-seated upon this threaded end is a disc 25 having a notched or serrated periphery and interposed between said 25 disc and the member 17, is a washer 26.

The notched edge of disc 25 engages the bead or flange that is formed between the side wall and end of a can.

Rigidly secured to the intermediate portion 30 of jaw 12 and in the same vertical plane with shaft 22, is one end of a stud 27 that occupies a position directly above the end of shaft 22 that carries the toothed disc 25 and mounted to rotate freely upon said shaft is a disc 28, the size of 35 which is such that its periphery occupies a position immediately adjacent and spaced a slight distance apart from the points of the teeth on the periphery of disc 25. This disc 28 is retained on stud 27 by means of a washer 29 and a cotter 40 pin 30 that passes diametrically through the stud.

The periphery of disc 28 is formed with portions of slightly different diameters, thereby providing a groove or offset on a portion of the periphery of said disc and which arrangement accommodates 45 both upstanding and outwardly presented beads or flanges that are formed on the edges of the can between the side wall and end walls.

Positioned between the inner face of jaw 12 and the adjacent face of the disc 28, is a combined 50 puncturing and cutting member comprising a substantially rectangular body 31, in the upper portion of which is formed a notch 32 for the accommodation of a stud 27.

Formed through the end portions of the body 55 31, are threaded apertures 33 that receive the threaded ends of screws 34, which latter pass through apertures in the jaw member 12 and thus detachably secure the cutting member to said jaw.

Depending from the intermediate portion of the lower edge of plate 31, is a blade 34 having a beveled lower edge 35 that is inclined lengthwise and the lowermost portion of this beveled edge occupies a position just above the center of the shaft 22 that carries the notched disc 25, thus providing a point 36 that is adapted to puncture the can upon which the opener is used and the sharp edge on the lower end of the blade 34 extends forwardly and upwardly so as to cut through the thin sheet metal that forms the top of the can that is being opened.

In the use of my improved can opener, the handles 11 and 15 are swung away from each other on the pivot formed by rivet 13, thus separating the jaws 12 and 16 and the beaded edge of the can that is to be opened is positioned directly over the top of the toothed disc 25.

The handles 11 and 15 are now brought together by the pressure of one hand so that the point 36 punctures the top of the can immediately adjacent the bead on the edge thereof and as the jaws are brought together, the bead will be firmly clamped between the disc 28 and the teeth on the edge of disc 25.

Crank handle 21 is now manipulated so as to rotate pinion 20 and rotary motion will thus be imparted to gear wheel 24, shaft 22 and toothed disc 25, with the result that the can will be slowly rotated with the engaged bead passing between the edge of disc 28 and the teeth of disc 25, which teeth engage the bead so as to impart rotary motion to the can.

As the can is thus rotated, the sharp beveled edge 35 of the blade produces a clean edged cut through the top of the can immediately adjacent the bead on the edge thereof so that when the can has been completely rotated a clean edged disc of metal is cut from the top so that the contents of the can may be readily removed without encountering rough or jagged edges such as are produced by certain types of manually operated can openers.

I prefer to detachably mount the toothed disc 25 on the end of shaft 22 so that said disc when it has become worn or unfit for service may be removed and replaced by a new disc, but if desired this disc may be permanently secured to the shaft 22, either by being riveted thereon or keyed thereto.

The combined puncturing and cutting member may be readily removed from jaw 12 by withdrawing screws 34 and this permits the edge of the cutting member to be resharpened or said member may be discarded and replaced by a new cutting member.

The disc or wheel 28 that clamps the beaded edge of the can against the toothed disc 25, provides a rolling bearing for that portion of the bead that is directly engaged by the teeth of said disc 25 and as a result the rotation of the can when properly engaged by the jaws of the can opener may be readily accomplished and further, such operation is conveniently accomplished through the use of a crank handle and pinions of different sizes for imparting rotary motion to the shaft 22 that carries toothed wheel 25.

Thus it will be seen that I have provided a can opener that is relatively simple in construction, inexpensive of manufacture and very effective in performing the functions for which it is intended.

It will be understood that minor changes in the

size, form and construction of the various parts of my improved can opener may be made and substituted for those herein shown and described without departing from the spirit of my invention, the scope of which is set forth in the appended claims.

I claim as my invention:

1. A can opener, comprising a pair of pivotally connected handles, a double jaw on the forward end of one of said handles, said double jaw comprising spaced parallel members, a relatively short jaw on the forward end of the other handle, a shaft journaled in the members forming the double jaw, a gear wheel mounted on said shaft, a toothed wheel mounted on one end of said shaft, a second shaft journaled in the members forming the double jaw, a pinion carried by the second mentioned shaft, the teeth of which pinion mesh with the teeth of said gear wheel, a crank handle secured to said second mentioned shaft, a stud seated in the short jaw, a roller journaled on said stud and positioned above the toothed wheel on the first mentioned shaft and a pointed blade detachably secured to the short jaw adjacent said stud within the point of said blade overlying the face of said toothed wheel.

2. A can opener, comprising a pair of pivotally connected handles, a double jaw on the forward end of one of said handles, said double jaw comprising spaced parallel members, a relatively short jaw on the forward end of the other handle, a shaft journaled in the members forming the double jaw, a gear wheel mounted on said shaft, a toothed wheel mounted on one end of said shaft, a second shaft journaled in the members forming the double jaw, a pinion carried by the second mentioned shaft, the teeth of which pinion mesh with the teeth of said gear wheel, a crank handle secured to said second mentioned shaft, a stud seated in the short body, a roller journaled on said stud and positioned above the toothed wheel on the first mentioned shaft, a plate detachably secured to the inner face of the short jaw, said plate having a notch for the reception of the stud that is seated in said short body and a pointed blade depending from said plate with the point of said blade overlying the outer face of said toothed wheel.

3. A can opener, comprising a pair of pivotally connected handles, a double jaw on the forward end of one of said handles, said double jaw comprising spaced parallel members, a relatively short jaw on the forward end of the other handle, a shaft journaled in the members forming the double jaw, a gear wheel mounted on said shaft, a toothed wheel mounted on one end of said shaft, a second shaft journaled in the members forming the double jaw, a pinion carried by the second mentioned shaft, the teeth of which pinion mesh with the teeth of said gear wheel, a crank handle secured to said second mentioned shaft, a stud seated in the short jaw, a roller journaled on said stud and positioned above the toothed wheel on the first mentioned shaft, the periphery of which roller is formed at different diameters to provide a groove for the accommodation of the bead or flange on the edge of the can to which the opener is applied and a pointed blade detachably secured to the short jaw adjacent said stud with the point of said blade overlying the face of said toothed wheel.

FRANK F. HOSMER.
